UNITED STATES PATENT OFFICE.

NICHOLAS S. VEDDER AND FRANCIS RITCHIE, OF TROY, AND TOBIAS S. HEISTER, OF LANSINGBURG, ASSIGNEES TO NICHOLAS S. VEDDER, OF TROY, NEW YORK.

DESIGN FOR BASE-BURNING STOVE.

Specification forming part of Design No. **8,005**, dated January 12, 1875; application filed December 30, 1874.
[Term of Patent 3½ years.]

To all whom it may concern:

Be it known that we, NICHOLAS S. VEDDER, of the city of Troy, in the county of Rensselaer and State of New York, FRANCIS RITCHIE, of the said city of Troy, and TOBIAS S. HEISTER, of the village of Lansingburg, in the said county of Rensselaer, New York, have jointly invented and produced a new and original ornamental Design for Base-Burning Stoves, of which the following is specification, reference being had to the accompanying cut, print, or engraving of a stove having our said new design.

One part of this invention consists of the design for the urn A, composed of the ornamental scroll handles b, the enlarged upper part of the body ornamented by the band of diamond-shaped figures c and the rosette d, the funnel-form section e, having the tapering ribs or grooves and ornaments f thereon, and the swelling lower part, g, of the body ornamented by the row of beads h, and recesses h', all shaped and combined so as to appear as represented in the aforesaid cut.

Another part consists of the design for the upper section, I, composed of the series of engraved compound ornaments J, in the plain oblong panels K, separated by and alternating with the series of ornamental beads or moldings L, each of the said ornaments J being formed by a long upright-jointed stem, extending from a scroll base, and having pendant flower-branches, and upward and downward inclined curved and pointed leaves and bracts, as shown, and the whole shaped and arranged together so as to present substantially the same appearance as is represented in the aforesaid print.

Another part consists of the design for the doors M of the upper illuminating section, the same being composed of the outer ornamental border n, having an obtuse-angled dentate outer edge, the two curved stiles o o, with flaring tops, between three circular arches, p, over the mica openings q, the outermost side bands r terminating in scrolls at the two rounded upper corners of each door, the double

scroll-bands s s over the two outer arches, and the two central scrolls t over the middle arch, all shaped, ornamented, and combined as represented in the aforesaid engraving.

Another part consists of the design for the doors U of the lower illuminating section, composed of the outer ornamental border v, having transverse ribs and an obtuse-angled dentate outer edging, the single upright stile w between the two mica-light openings, having flat arched tops x, and the outer side moldings y y terminating in scrolls on each side of the central cap-piece z, all shaped, ornamented and disposed as represented in the aforesaid print.

Another part consists of the design for the side panel B of the lower base section, composed of the series of compound ornaments a, arranged in the series of oblong upright panels i, between and alternating with the series of columns j, all shaped, ornamented, and arranged together, and between the bottom plate C and the top plate D of the lower base section, so as to appear substantially as represented in the aforesaid engraving.

What we claim as our joint invention is—

1. The design for the urn A, composed of the handles b, figures c, and rosette d on the enlarged upper part of the body, ornaments f on the funnel-shaped section e, and beads h and recesses h' on the swelling lower part g, all shaped, ornamented, and combined as specified and shown.

2. The design for the upper section, I, composed of the series of engraved compound ornaments J, panels K, and beads or moldings L, all shaped, ornamented, and arranged together as shown and described.

3. The design for the doors M, composed of the outer border n, stiles o o, scroll-ended side moldings r r, double scroll-bands s s, and central cap-scrolls t, all shaped, ornamented, and arranged together as shown and described.

4. The design for the doors U, composed of the ornamental border v, stiles w, two mica-light openings, having flat-arched tops x, scroll-ended side and top moldings y y, and

central cap-piece *z*, all shaped, ornamented, and arranged together as shown and specified.

5. The design for the side panel *B*, composed of the compound ornaments *a*, panels *i*, and columns *j*, all shaped, ornamented, and arranged together and between the plates *C* and *D*, as shown and described.

In testimony whereof we hereunto subscribe our names this 24th day of December, 1874.

NICHOLAS S. VEDDER.

FRANCIS RITCHIE.

TOBIAS S. HIEISTER.
